UNITED STATES PATENT OFFICE.

ERNEST O. CARTWRIGHT, OF SPRINGFIELD, OHIO, ASSIGNOR TO CHARLES F. GARDNER,
OF SPRINGFIELD, OHIO.

WATER-ELEVATING APPARATUS.

1,383,599.

Specification of Letters Patent.

Patented July 5, 1921.

Application filed June 10, 1919, Serial No. 303,068. Renewed May 19, 1921. Serial No. 470,946.

To all whom it may concern:

Be it known that I, ERNEST O. CARTWRIGHT, a citizen of the United States, residing at Springfield, in the county of Clark, 5 and State of Ohio, have invented a new and Improved Water-Elevating Apparatus, of which the following is a specification.

My invention relates to a device for utilizing the city water service supply for pumping or elevating a supply of cistern water to the distributing pipe system of a house whereby advantage may be taken of the high pressure of the city service for automatically maintaining an adequate supply of 10 pure water for consumption in the house. It frequently happens that the water supply of cities is not of the required softness for domestic use and it is frequently desirable to obtain the domestic water supply from another source, usually a cistern or well. More 15 adequate means, therefore, must be provided for delivering the soft water from the cistern or well into the service pipes of the residence and my invention provides a means 20 for this purpose which is operated and obtains its motive power from the city supply mains.

In its generic nature, the present invention 25 comprises a hydraulic pumping apparatus so arranged and designed as to be operated by the pressure water from the city mains to elevate the cistern or well water and deliver it under adequate head to the service pipes of the residence and maintain a sufficient 30 pressure therein to cause delivery of the water from the outlets of the house piping system at the highest elevation desired.

An object of the invention is to provide an 35 apparatus of the character stated of an efficient construction simple in its arrangement of parts and of low first cost and maintenance so as to enable the production of an apparatus which can be installed in a residence at a low expense and will be self- 40 maintaining, requiring but little attention and fully automatic in its operation.

In its more specific nature, the invention 45 involves those novel details of construction, combination and arrangement of parts, all 50 of which will be first fully described and then be specifically pointed out in the ap-

pended claims, reference being had to the accompanying drawings, in which:—

Figure 1 is a side elevation, the oil reservoir being shown in section and illustrating 55 the invention.

Fig. 2 is a central side elevation and part central vertical section, parts being broken away, illustrating the invention.

Fig. 3 is a horizontal section on the line 60 3—3 of Fig. 2 looking in the direction of the arrow.

Fig. 4 is a vertical section on the line 4—4 of Fig. 3 looking in the direction of the arrow.

Fig. 5 is a vertical section on the line 5—5 65 of Fig. 3 looking in the direction of the arrow.

Fig. 6 is an enlarged horizontal section taken substantially on the line 6—6 of Fig. 1. 70

Fig. 7 is a detail elevation, parts being broken away, of the two control valves and the throw-over weight lever that co-operates therewith.

Fig. 8 is a detail section and part elevation of a portion of the apparatus. 75

Figs. 9 to 12, inclusive are diagrammatic views illustrating the action of the valve devices.

Referring now to the accompanying drawings, in which like letters and numerals of reference indicate like parts in all of the figures, 1 is a base casting which is provided with a duct 2 from a port 3 for delivering the spent pressure water to waste. The casting 80 1 is also provided with a port 4 for each high pressure cylinder which is connected with the hollow piston rods 7 of the respective pressure cylinders by a duct 5. In the preferred arrangement I provide at least 85 two sets of cylinders, i. e., two pressure cylinders and two secondary cylinders, there being a pressure cylinder (primary) and a secondary cylinder to each unit.

7 designates the hollow piston rods of the 90 pressure cylinders 9, the piston rods 7 being threaded into the casting 1 at 6 (see Fig. 2) and being provided with packing members 8, as indicated. Each set of cylinders, namely, 95 a high pressure cylinder 9 and a low pressure cylinder 28, are united as a unitary structure, 100 preferably by being integrally cast as a sin-

gle casting, 10—11, respectively. Thus, it will be seen, that the cylinder casting 10 having a primary cylinder 9 and a secondary cylinder 28, will move as one unit while the casting 11, containing a primary cylinder 9 and a secondary cylinder 28, will move as another unit.

12 designates pin plugs which carry pins 13 on which suitable weights 14 are located, 10 there being at least one weight 14 for each casting. The amount of weight 14 employed will depend upon the pressure in the city mains, as will be later more clearly understood.

15 The ports 3 and 4 are controlled by an oscillating valve 15 which has an internal chamber for effecting communication at times between the ports 3 and 4 and at other times closing off the ports 4 from communication with the port 3 and permitting the pressure water from the city service mains to flow via the duct 20 in the cap 19 to the ports 4. The valve 15 includes a flange 16 which rests against the adjacent surface of 20 the casting 1 and also includes a shank 17 which has a bearing fit in a suitable bore in the casting 1, (see Fig. 2). The stem or shank 17 has a squared projection 18 which enters the similarly apertured portion 22 of 25 the lever 21, the latter having a weight 23 at its end for a purpose presently explained. The weight lever 21 is provided with arms 24—25 which project into slotted links 26—27, respectively that are carried by the 30 castings 10—11, respectively.

35 29 designates the hollow piston rods for the secondary cylinders 28, the said rods having packing members 30 and being threaded into the casting 1 at 31 to communicate with the ducts 32 that in turn communicate with the ports 33, the latter being controlled by a second controlling valve 15^x whose flange 16^x seats against the adjacent face of the casting and which is provided 40 with a bearing shank 17^x and squared end 45 18^x, the latter projecting into the opening 22 of the weight lever whereby both valves 15 and 15^x and lever 21 will oscillate in unison, 50 35 is the suction duct which is adapted to be piped up with the cistern or well 43 by 55 a duct 44 (see Fig. 1) and deliver water to the port 34 from which it flows via the interior chamber of the valve 15^x to one or the other of the ports 33, according as the 60 same is opened. 36 is a cap placed over the valve 15^x and ports 34—33 and having a duct 37 which is connected at 38 to the standpipe 39 of the house piping system, from which standpipe the delivery pipes 65 40 radiate. The standpipe 39 is capped at 41 to provide an air cushion in the upper end of the standpipe, in which chamber the air may be compressed by the water column, as will be later understood.

65 The castings 10—11 are slotted as at 42

to allow for the movement of the weight lever 21, and the base casting 1 is similarly slotted for a similar purpose.

The base 1 and the cylinder castings 10—11 when in the lower position are immersed 70 in oil 46 contained in a tank or reservoir 45 in which the parts are set so as to provide a constant source of lubrication for the moving parts, thus making it unnecessary for an attendant to oil the parts from time to 75 time.

The average pressure of water in house service pipes is about 40 pounds, which is equal to a head of 92.3 feet. The average height to which it is desirable to elevate 80 soft water is about 37 feet to give good pressure for a shower on the second floor. Therefore, it is possible that 2½ times the quantity of soft water can be raised to a height of 37 feet by a unit quantity of 85 pressure water at 92.3 feet head. It is this principle that I have utilized in my present apparatus and by using the pressure water of the city service mains to elevate a weight as heavy as it will handle and to take advantage of the energy of the lifted weight to force the soft water to a level as high as it will handle I am enabled with my apparatus to reduce the friction loss to the minimum.

95 In general, the operation of the device may be best explained as follows: Calculation of the weight of the castings 10—11 is made and such additional weights 14 are applied as will be necessary to make the 100 weight of the castings slightly less than the equivalent of the pressure head of the city water supply so that when the pressure thereof is admitted into the cylinders 9, the said cylinders will be gradually raised by 105 the pressure therein and thus cause a suction in the secondary cylinders 28 to draw the water in the cistern or well into the same on the up-stroke of the cylinder.

110 The city water supply is connected to the duct 20 and maintains a constant pressure therein. Assume the valves to be in the position indicated in Figs. 9 and 10, the city pressure is being supplied to the right hand port 4 in Fig. 10 and is elevating the 115 casting 11, containing the cylinders 9 and 28 of that unit. As this occurs, the casting 11 will be elevated, thus sucking water into the cylinder 28 through the hollow piston rod 29 via the port 33 at the left in 120 Fig. 9 which at this time is in communication with port 34 that connects with the suction duct 35. As the casting 11 rises, the link 27 will, by engaging the arm 25, rock the lever 21 toward a vertical position 125 and as soon as the lever 21 has reached the vertical position (see Figs. 4 and 5) and passed slightly beyond the same, gravity will come into play to cause the said lever 21 to be quickly swung over to the opposite 130

side, thereby closing the ports 4, at the right in Fig. 10, and 33, at the left in Fig. 9, and opening the port 4 at the left in Fig. 10, and closing the port 33 at the right in Fig. 9, 5 from communicating with the respective ducts 20 and 37, and at the same time bringing the duct 4 at the right in Fig. 10 in communication with the port 3 (see Fig. 12) so that the water within the pressure cylinder 9 may be free to exhaust through the waste duct 2 so that the pressure therein from the duct 20 can now enter the left hand port 4 in Fig. 12, and be delivered to the cylinder 9 of the casting 10 to raise 10 it to the vertical position.

When the valve has been thus thrown over so as to bring the port 33 at the right in Fig. 9 into communication with the port 34 (see Fig. 11) the port 33 at the left in Fig. 9 will 20 be brought into communication with duct 37 so that the water in the cylinder 28 of the casting 11 (see Fig. 11) will be free to flow into the standpipe 39 via the duct 38.

Now, assume that the pressure water from 25 the city mains is applied to the duct 20 and the duct 37 connected with the house service pipes, all of which are filled with water and the outlets 40 thereof closed. At this time, one of the castings 10 and 11 will be at the 30 upper extremity of its limit of travel and the valves 15—15^x will be held by reason of the engagement of the links 26—27 with the respective arms 24—25. It should be understood right here that the valves 15—15^x and 35 weighted lever 21 are so fixed that they will not rest in equilibrium when arms 24—25 are released from engagement by the links 26—27 and it should be further understood that when the valves are in the horizontal 40 position shown in Figs. 4 and 5, the ports 4 on the pressure side are closed off from the supply duct 20 but slightly opened to communicate through the interior of the valves with the waste port 3 (see Fig. 5) while the 45 ports 33 on the house service side are both slightly opened to effect communication between the ducts 32 and 37 and shut off communication between ducts 32 and port 34 (see Fig. 4). As soon as one of the taps 40 50 is opened the equilibrium will be broken and the cylinder casting 10 or 11 will start to fall, due to the escape of the water from the cylinders 28 through the slightly opened ports 33 to the service duct 37, thus releasing the links 26—27 from arms 24—25, thereby 55 allowing the weight 23 to fall over to one side or the other as the case may be. The falling over of the weight 23 causes the valves to be rocked over to a position to 60 bring them as shown in Figs. 9 to 12, inclusive, thereby admitting pressure water into one cylinder 9 and again raising that cylinder to its maximum height while the other casting is descending to force the water 65 from the chamber 28 into the standpipe 39.

While I have shown my invention as embodying but two sets of cylinders, it is obvious that the number of sets may be increased as desired, the greater the number of sets, the more uniform the flow of water in 70 the house piping system, will be.

From the foregoing description, taken in connection with the accompanying drawings, it is thought the complete construction, operation and advantages of my invention will 75 be readily understood by those skilled in the art and I desire it understood that changes in the details of construction, combination and arrangement of the parts may be made without departing from the spirit of the invention or the scope of the appended claims. 80

What I claim is:—

1. An apparatus of the class described, a primary and a secondary cylinder joined together, relatively fixed primary and secondary pistons coöperative with said cylinders, means including a shiftable valve device for delivering pressure fluid to the primary cylinder and exhausting the same therefrom to raise said cylinder and allow 90 the same to fall again, means including a shiftable valve device for admitting water from a source of supply into said secondary cylinder as said cylinders rise and permitting the same to be expelled from said secondary cylinder as the cylinders fall, a source of pressure fluid supply coöperative with said primary cylinder and a source of service water supply and a service delivery piping system coöperative with said secondary cylinder. 95

2. In apparatus of the class described, a primary and a secondary cylinder joined together, relatively fixed primary and secondary pistons coöperative with said cylinders, means including a shiftable valve device for delivering pressure fluid to the primary cylinder and exhausting the same therefrom to raise said cylinder and allow 105 the same to fall again, means including a shiftable valve device for admitting water from a source of supply into said secondary cylinder as said cylinders rise and permitting the same to be expelled from said secondary cylinder as the cylinders fall, a source of pressure fluid supply coöperative with said primary cylinder and a source of service water supply and a service delivery piping system coöperative with said secondary cylinder, and including a standpipe having an air chamber, said cylinders being of sufficient weight to cause compression of the air in said chamber. 110 115 120

3. In apparatus of the class described, a cistern, a service pipe system including a standpipe having an air cushion chamber, a source of motive fluid supply and an elevating apparatus which includes primary and secondary cylinder and piston sets and control valve mechanism for admitting the mo- 125 130

tive fluid to and exhausting it from said primary cylinder to raise both of said cylinders, control valve mechanism for admitting service water from the cistern to said secondary cylinder and delivering it from the said secondary cylinder to the service standpipe and means governed by the rise of the cylinders for shifting said valve mechanisms.

4. In apparatus of the class described, a 10 cistern, a service pipe system including a standpipe having an air cushion chamber, a source of motive fluid supply and an elevating apparatus which includes primary and secondary cylinder and piston sets and con-

15 trol valve mechanism for admitting the motive fluid to and exhausting it from said primary cylinder to raise both of said cylinders, control valve mechanism for admitting service water from the cistern to said secondary 20 cylinder and delivering it from the said secondary cylinder to the service standpipe and means governed by the rise of the cylinders for initiating the shifting of said valve mechanisms in unison.

25 5. In apparatus of the class described, a plurality of sets of primary and secondary cylinders and pistons therefor, a control valve for each pair of primary cylinders and pistons, another con- 30 trol valve for each pair of secondary cylinders and pistons, a source of pressure water and an exhaust duct therefor, co-operatively connected with said primary cylinders, the pressure water inflow 35 and outflow to and from said primary cylinders being governed by the control valve therefor, a source of service water supply and a service water distributing pipe system co-operative with said secondary cylinders and controlled by the control valve 40 therefor.

6. In apparatus of the class described, a plurality of sets of primary and secondary cylinders and pistons therefor, a control 45 valve for each pair of primary cylinders and pistons, another control valve for each pair of secondary cylinders and pistons, a source of pressure water and an exhaust duct therefor, co-operatively connected with said primary cylinders, the pressure water inflow 50 and outflow to and from said primary cylinders being governed by the control valve therefor, a source of service water supply, a service water distributing pipe system co- 55 operative with said secondary cylinders and controlled by the control valve therefor, and means operated by the movement of said cylinders for controlling the action of said valves.

60 7. In apparatus of the class described, a plurality of sets of primary and secondary cylinders and pistons therefor, a control valve for each pair of primary cylinders and pistons, another control valve for each pair

of secondary cylinders and pistons, a source 65 of pressure water and an exhaust duct therefor co-operatively connected with said primary cylinders, the pressure water inflow and outflow to and from said primary cylinders being governed by the control valve 70 therefor, a source of service water supply, a service water distributing pipe system co-operative with said secondary cylinders and controlled by the control valve therefor, and means operated by the movements of said 75 cylinders for initiating the operation of said valves and other means for completing said operation.

8. An apparatus of the class described, a base, primary and secondary hollow piston 80 rods and pistons mounted on said base, primary and secondary cylinders co-operative with said pistons and adapted to rise and fall on said rods, a control valve mounted in bearings in said base for said primary cylinders and another control valve mounted on said base for said secondary cylinders, ducts for delivering pressure fluid via said first mentioned valve to said primary cylinders and exhausting the same therefrom, other 90 ducts for delivering service water to said secondary cylinders and delivering the same therefrom, said other ducts being controlled by the valve for said secondary cylinders, means governed by the movement of said 95 cylinders for initiating the shifting movement of said valves and other means common to both valves for completing the shifting movement.

9. An apparatus of the class described, a 100 base, primary and secondary hollow piston rods and pistons mounted on said base, primary and secondary cylinders co-operative with said pistons and adapted to rise and fall on said rods, a control valve mounted in 105 bearings in said base for said primary cylinders and another control valve mounted on said base for said secondary cylinders, ducts for delivering pressure fluid via said first mentioned valve to said secondary cylinders 110 and exhausting the same therefrom, other ducts for delivering service water to said secondary cylinders and delivering the same therefrom, said other ducts being controlled by the valve for said secondary cylinders, 115 means governed by the movement of said cylinders for initiating the shifting movement of said valves, other means common to both valves for completing the shifting movement and an oil reservoir in which the 120 moving parts of the aforesaid structure are immersed.

10. In apparatus of the class described, a body having a primary cylinder and a secondary cylinder, a piston held in each cylinder, means for delivering motive fluid to and exhausting the same from said primary cylinder to raise the cylinders and permit 125

- the same to fall, a source of service water supply, means for delivering city service water from the source of supply to said secondary cylinder as said cylinder is raised, 5 means for delivering the water from said secondary cylinder to the distributing service pipes, and an oil reservoir in which the moving parts of the aforesaid structure are immersed.
- 10 11. In apparatus of the class described, a base having a pair of pressure ports and a single exhaust port coöperating therewith, a pair of pressure piston rods respectively in communication with the respective pressure ports, a control valve mounted on the base for governing the communication between the aforesaid ports, means for delivering pressure fluid to said control valve for distribution to the respective pistons, 15 said base having a suction duct and port and a pair of distributing ports, a pair of secondary pistons in communication respectively with the respective distributing ports, a control valve governing the communication between said suction duct port and said distributing ports, an outlet duct also coöperating with said last named control valve for delivering 20 water from said distributing ports, a pair of bodies each including a primary and a secondary cylinder coöperative respectively each with one of the primary and one of the secondary pistons, means for shifting 25 the respective valve devices to alternately supply pressure water to the respective primary pistons and cylinders and exhaust the same therefrom, said means comprising link members carried by the cylinder bodies, arms connected with the respective valves and coöperating with the link members and an overbalancing weight connected with the valves.
- 30 a primary and a secondary cylinder coöperative respectively each with one of the primary and one of the secondary pistons, means for shifting the respective valve devices to alternately supply pressure water to 35 the respective primary pistons and cylinders and exhaust the same therefrom and govern the flow of water to said outlet duct.
12. In apparatus of the class described, a base having a pair of pressure ports and a single exhaust port coöperating therewith, a pair of pressure piston rods respectively in communication with the respective pressure ports, a control valve mounted on the base for governing the communication between the aforesaid ports, means for delivering 40 pressure fluid to said control valve for distribution to the respective pistons, said base having a suction duct and port and a pair of distributing ports, a pair of secondary pistons in communication respectively with the respective distributing ports, a control valve governing the communication between said suction duct port and said distributing ports, an outlet duct also coöperating with 45 said last named control valve for delivering water from said distributing ports, a pair of bodies each including a primary and a secondary cylinder coöperative respectively each with one of the primary and one of the secondary pistons, means for shifting 50 the respective valve devices to alternately supply pressure water to the respective primary pistons and cylinders and exhaust the same therefrom, said means comprising link members carried by the cylinder bodies, arms connected with the respective valves and coöperating with the link members and an overbalancing weight connected with the valves.
- 55

ERNEST O. CARTWRIGHT.
